UNITED STATES PATENT OFFICE.

ANDREW P. NICHOLS, OF TACOMA, WASHINGTON.

TRACK-GAGE.

SPECIFICATION forming part of Letters Patent No. 758,461, dated April 26, 1904.

Application filed September 8, 1903. Serial No. 172,328. (No model.)

To all whom it may concern:

Be it known that I, ANDREW P. NICHOLS, a citizen of the United States, residing in Tacoma, in the county of Pierce and State of Washington, have invented certain new and useful Improvements in Track-Gages, of which the following is a specification.

My invention relates to devices for measuring the gage or distance between the rails of a railroad-track and for moving one of said rails to any required gage, and has for its objects, first, to provide a device which will measure the gage accurately; second, to provide a device by which one rail may be forced 15 to any gage and which will indicate the gage at any time; third, to provide a device which may be readily disconnected and packed into small space, and, fourth, to provide an adjustable device which may be used with any 20 of several sizes of rails and which is quickly altered for any rail whatever. I attain these objects by the mechanism illustrated in the accompanying drawings, in which—

Figure 1 is a plan, and Fig. 2 is a side elevation, of my device in use. Fig. 3 is an enlarged plan, partly in section, of the operating mechanism, the upper set of links and the gage-indicator being removed. Fig. 4 is a perspective view of the adjustable rail-claw 25 inverted, and Fig. 5 is a vertical longitudinal section theréof. Fig. 6 is an enlarged detail plan showing the gage-indicator. Fig. 7 is a section on line 7 7, Fig. 3.

Similar letters of reference refer to similar parts throughout the several views.

My device consists of a claw engaging the fixed rail, a claw engaging the rail to be moved, an adjustable toggle connection between the claws for forcing them either toward each other or apart from each other, and means for indicating the distance between said claws. The invention also includes means for altering the claws so as to fit rails of various sizes.

The claw A, which is intended to engage the fixed rail, consists of a casting with four lugs extending therefrom, as shown in Fig. 4. The inside pair of lugs B engage the inside of the rail and form the point from which the gage 50 is measured. The outside pair of lugs B' en-

gage the outside of the rail and are placed sufficiently far from the inside pair of lugs to accurately span the head of the largest rail to be used.

Within the casing A and near the outer lugs B', I provide a recess C, in which are placed a series of thin plates D, which are respectively pivoted on a pin E, extending across the recess adjacent to and below lugs B'. These plates D are arranged so that one or more of them can be turned upon the pin E, so as to be against the outer lugs B', as indicated in Fig. 5, and reduce the distance between the outer and inner lugs more or less, as desired, to make the claws fit the different sizes of rails. A spring F is adapted to press against the hinged ends of the plates D, so as to hold them either in their raised or lowered positions. I find that about three plates D are sufficient for use on most railroads; but if more are needed the pin E may be removed and additional plates D placed within the recess C.

The claw G, which is intended to engage the rail to be moved, may be provided with only one inner lug H and one outer lug H', but is in other respects similar to the above-described claw A and should have adjusting-plates D therein similar to those above described.

The claws A and G are respectively connected to the outer ends of rods or pipes J, the inner ends of which are connected to adjustable hollow pieces K K', which are slidably mounted on and alined by a bar L, which guides the pieces K and keeps the claws A and G always in line. The piece K' is pivotally connected by links M' to nuts N at opposite sides of bar L, and piece K is also pivotally connected by links M to said nuts, the links and nuts forming a toggle-joint connection between the pieces K, the elbows of the toggle-joints being the nuts N, through which pass the right and left handed screw O, having a suitable hand-lever P on its end. This screw O passes freely through an opening in the center of the bar L, but need not be secured to it in any way. By turning the screw O the nuts N are drawn toward or away from each other and the pieces K, sliding on the bar L, correspondingly forced apart or toward each other, and

as there is a direct rigid connection between the pieces K and the claws A and G engaging the rail-heads the said claws and rails are correspondingly moved away from or toward each other, according to which way the screw-rod O is turned.

Fig. 6 illustrates an automatic indicator, whereby the gage may be told at any time. This consists of two metal pieces Q and R, respectively secured to the sliding pieces K K' and dovetailed so as to allow one part to slide over the other and to keep in close contact with it. The lower piece Q has scale-marks thereon, and the inner end of the upper piece R runs as an indicator therefor and shows when the gage is of the desired length. In the figure the upper piece R is slid farther than is ordinarily necessary to show the gage-marks on the piece Q. The figures "8½" and "9" indicate the position of the end of R when the distance between the rails is respectively four feet eight and one-half inches and four feet nine inches. When the parts are secured together, it can be taken to pieces by unscrewing the claws A and G from the pipes J and by unscrewing the pipes J from the pieces K.

I have illustrated a toggle-joint connection between the parts; but I do not confine myself to the use of a toggle-joint, but could equally well place the right and left handed screw-bar at right angles to its present position and screwing direct into the pieces K or, in fact, any of the well-known devices for shortening or lengthening the distance between the claws.

What I claim, and desire to secure by Letters Patent, is—

1. In a track-gage, the combination with devices adapted to engage the rails, of an adjustable toggle connection between said devices.

2. In a track-gage, the combination with claws or devices adapted to engage the rails, of an adjustable toggle device for changing the distance between said devices, and means for keeping said devices in alinement.

3. In a track-gage, the combination with devices adapted to engage the rails, of a toggle device for changing the distance between said devices, and means for indicating the distance therebetween.

4. In a track-gage, the combination with a claw adapted to engage both sides of a rail, of an adjustable plate adapted to change the width of said claw, substantially as described.

5. In a track-gage, the combination with claws adapted to engage the rails, of a sliding connection between said claws, and a toggle device for controlling said sliding connection.

6. In a track-gage, the combination with claws adapted to engage the rails, of a connection between said claws, a toggle for con-

trolling said sliding connection, and means for indicating the distance between said claws.

7. In a track-gage, the combination with claws adapted to engage the rails, of a toggle connection between said claws, and a hand-operated screw mechanism whereby said sliding connection is controlled and operated.

8. In a track-gage, the combination with claws adapted to engage the rails, an adjustable connection between said claws, of a pair of dovetailed pieces adapted to slide with respect to each other, and having an index thereon whereby the distance between said claws may be shown, said pieces being connected to opposite members of said connection.

9. In a track-tool, the combination of a claw adapted to engage a fixed rail and having a broad surface along both sides of said rail, of a claw adapted to engage the movable rail and having a narrow surface along both sides of said rail, and of means whereby said claws are drawn toward each other or are forced apart.

10. In a track-tool, the combination of claws adapted to engage both the inner and outer sides of the rails; with plates adapted to reduce the width of said claws, substantially as described.

11. In combination, opposite sleeves, the intermediate nuts, links connecting the sleeves and nuts, and forming a toggle, a double-ended screw engaging said nuts, and rail-engaging devices attached to said sleeves, substantially as described.

12. In combination, a rod, sleeves movable thereon, nuts at opposite sides of said rod, links pivotally connecting the sleeves and nuts forming a toggle; a double-ended screw engaging said nuts, and opposite rail-engaging devices, connected to said sleeves, substantially as described.

13. In combination with a rail-engaging claw having a recess in its face above the rail, a series of plates hinged in said recess, and adapted to be turned down to reduce the width of the claw-grip, substantially as described.

14. In a track-tool, the combination of a claw adapted to engage the inner and outer sides of the rails, and having a recess, plates in said recess adapted to be turned into position to engage one side of the rails to narrow the grip of said claw, and a spring adapted to hold said plates in either position, substantially as described.

In testimony whereof I have signed my name to this specification in the presence of two subscribing witnesses.

ANDREW P. NICHOLS.
